UNITED STATES PATENT OFFICE.

FRANK R. BRIGGS AND GEORGE T. MCLEOD, OF BROOKLINE, MASSACHUSETTS, ASSIGNORS TO THOMAS G. PLANT COMPANY, OF ROXBURY, MASSACHUSETTS, A CORPORATION OF MASSACHUSETTS.

SHOE AND HEEL THEREFOR.

Application filed July 19, 1922. Serial No. 576,105.

To all whom it may concern:

Be it known that we, FRANK R. BRIGGS and GEORGE T. MCLEOD, citizens of the United States, and residents of Brookline, in the county of Norfolk and State of Massachusetts, have invented an Improvement in Shoes and Heels Therefor, of which the following description, in connection with the accompanying drawings, is a specification, 10 like letters on the drawings representing like parts.

Our present invention relates to shoes, and more particularly to an improved shoe structure having a novel form of heel construction.

In the art of manufacturing boots and shoes it is very desirable to provide a structure which will incorporate in a shoe an arch supporting feature, and heretofore this has 20 been attempted by making individual and specially formed shank stiffeners, arch supports, orthopedic heels of varying shapes and thicknesses and the like. Thus for example oddly shaped heels having an extended portion at the inside of the shoe have 25 been made, and such heels having greater thickness at the inner or arch part of each shoe have been tried, in order to supply an arch supporting or orthopedic feature to 30 the shoe itself. Such prior devices, however, have been unsatisfactory, and ungainly in appearance, as well as expensive, distorting the shoe, or distorting the heel, either by excessive length at one side or excessive 35 thickness, produce an ill-shaped and undesirable appearing shoe.

In our present invention we have obviated the difficulties above briefly outlined and have provided a shoe structure with an arch 40 supporting feature enabling the shoe and the heel to be of normal size, attractive design, uniform thickness and extent, utilizing a straight or curved heel breast as desired, and yet to produce an arch supporting effect 45 by varying the resiliency afforded by the heel structure.

We have devised a shoe with a resilient heel wherein the outer edge portion of the heel, i. e., the right hand portion for the 50 heel on the right shoe and the left hand portion for the heel on the left shoe, is of greater, or "double", resiliency than the inner and forward portion. This feature produces important results in that the

greater resilient portion is usually the first 55 to take the jar of landing on each step during walking and thus provides resiliency where it is needed, whereas the other portion of the heel can be made to give a rigid 60 supporting feature by being of less resiliency. In other words, the greatest yield is desired at the outer and rear section of the heel whereas the greatest compression is desired at the inner and forward section of the heel. Our invention accomplishes this 65 result. Thus we so form our present improved shoe and heel that the outside portion will be of greater resiliency than the inner side of the heel, viz: that part next 70 the greater curve of the arch in the shoe, which may be partially non-resilient or of less resiliency compared with the outer portion of the heel. This construction allows the foot of the wearer, and each foot, during 75 walking, to effect an automatic or "self-seating" pressure upon the shoe heel, giving an arch supporting result along the lesser resiliency portion of the heel and side, while affording greater, or even double, resiliency 80 on the outer edge where the jar of walking is felt. Thus we secure the effect of an orthopedic heel having greater thickness or greater length, without, however, distorting either side, length, or appearance of the 85 shoe and heel, and therefore combining these 90 advantages in a desirable way with an attractive appearance and economy of construction. By making our heel of uniform and standard size, it may be readily applied, and the shoe built without special operations, 95 machines or hand appliances.

Furthermore, an important feature consists in the economy of material used, as well as in the utilization of present standard methods of boot and shoe manufacture in 95 applying the heel thereto.

In carrying out our invention we may form a heel partly of one thickness of resilient material, such as rubber or rubber composition, and partly of another thickness, or 100 partly of non-elastic material, relatively with the resilient portion. Thus we may form our shoe and heel with a rubber and fiber section, preferably building and molding the heel with these varying substances, 105 so that a complete heel is supplied for the heel attaching operation in building the shoe. Leather, wood, or hard vulcanized

material or compound can be used for the relatively non-elastic section or portion of the heel. Preferably, also this non-elastic portion will be covered by a resilient toplift, 5 or may be covered by a portion of the resilient section of the heel, making the same integral, either method and article being feasible in carrying out our invention, and both being included in the broader of the claims 10 herein. Where a separate toplift is used, the same can be renewed and repaired by the simple addition of such cushioning layer, and thus the life of the heel and the usefulness of the shoe can be prolonged 15 without requiring the necessity of removing the entire heel.

Further objects and advantages of our present invention will be more fully pointed out and claimed.

20 Referring to the drawings, illustrating a preferred embodiment of the invention, Fig. 1 illustrates a plan view of our improved heel;

Fig. 2 is a cross-sectional view on the 25 line 2—2 of Fig. 1;

Fig. 3 is a similar cross-sectional view with the relatively non-resilient section removed; and

Fig. 4 is a cross-sectional view illustrating the shoe heel in layers with a renewable 30 toplift;

Fig. 5 being a view on a reduced scale of our improved shoe with the heel attached.

We may make our improved heel of sufficient size for the entire heel structure of the shoe, or we may make the same to be applied to a shoe on the usual heel base, the latter being shown in Fig. 5. In either event the advantages of our invention are obtained 40 and varying resiliency in the heel and the orthopedic feature in the shoe are secured.

As shown in the drawings, our improved heel comprises a resilient portion, illustrated in Figs. 1, 2 and 3, as comprising the outer 45 section of the completed heel 1, and the tread surface or toplift portion 2, the latter extending entirely across the width of the heel, and taking the place of the toplift. When made of rubber or rubber compound, this portion of the heel is preferably molded 50 with a recess or groove 3, and preferably with a beveled face 4, to which is applied the relatively non-resilient portion 5. The latter is of suitable size and form to fit in the recess 3 and preferably also is applied thereto while the portions 1 and 2 of greater resiliency are still in plastic or "tacky" condition, so that the non-resilient member 5 will adhere thereto. It is feasible to utilize 60 the member 5 as a loose part of the mold if desired, and thus complete the molding of the heel at one operation. This non-resilient section 5 being of leather, fiber, vulcanized rubber or the wood or other relatively hard substances, and being posi-

tioned on the inside of the shoe, produces an arch supporting effect of an orthopedic heel or shoe, as above briefly explained by decreasing the resiliency of the entire heel. Furthermore, the protecting layer of the 70 resilient portion 2 protects this entire non-resilient portion 5, and thus the full effect of the ordinary rubber or rubber-compound toplift is obtained. It will be appreciated that our improved heels will be made right 75 and left for application to the corresponding shoes of a pair, and of suitable size and in desired design, presenting the exterior appearance of finished heel structures, without distortions of thickness, length or the like. 80

In Fig. 4 we have illustrated the formation of our heel wherein the non-resilient part 5 is built up in a laminated heel, the resilient portion of the heel comprising two or more layers or sections 6, 6, and a full 85 toplift layer 7, the latter being of several layers if desired. In this form of our improved heel, the toplift layer 7 can be renewed at any time without unduly disturbing the portions 5 and 6, and thus facilitates repairing of the shoe at minimum expense and long usefulness in the heel.

As illustrated in Fig. 5, the shoe 10 may have a usual heel base 12, to which our improved heel is applied. In this shoe the 95 inside edge is considered as in view, that is, this shoe being the "right" shoe of a pair. Therefore the non-resilient section 5 and the portion 2 or separate toplift layer 7 appears. In the act of walking the wearer will obtain 100 the benefit of an arch supporting and an orthopedic feature along the inner edge of the arch of each foot, through the non-compressibility of the layer 5 relatively with the outer portion of the heel, as above explained.

Our improved form of heel can be attached by any desired means, or by the usual heel nailing operation, preferably the non-resilient portion 5 being of a substance 110 readily penetrable by shoe nails. Furthermore, the nail retaining washers can be molded in this heel if desired. Thus we obtain the advantages of a moldable as well as free nailing resilient shoe heel, and with the non-resilient portion giving a greater tenacity to the heel attaching nails, eliminating the danger of the heel being torn off—a difficulty with present all-rubber 115 heels.

Our improved shoe and novel heel can be manufactured without unusual expense, extra machines, or difficult hand operations, and thus can be economically made by present modern shoe factory methods, labor and working conditions, and minimum expense for work and material.

Our invention is further described and defined in the form of claims as follows:

1. An improved arch supporting boot or 120

shoe, having a heel structure formed with a relatively resilient section on the outer edge of the heel, and a relatively non-resilient section on the inner edge of each heel, in combination with a resilient toplift section.

2. An improved heel for boots and shoes, having a resilient cushioning portion, and a non-resilient portion, said non-resilient

portion being on the inside edge of the shoe, in combination with a resilient toplift covering both said portions.

In testimony whereof, we have signed our names to this specification.

FRANK R. BRIGGS.
GEORGE T. McLEOD.
